TRAILER COUPLING

Eugene Scott Baber, Indianapolis, Ind.

Application April 25, 1932. Serial No. 607,364

10 Claims. (Cl. 280—33.55)

This invention relates to the art of couplings and particularly to a coupling between trailers as employed in ash and garbage trains where a tractor is employed to pull a number of trailers 5 along the streets and alleys of cities. The trailers to which my invention is intended to be applied are first drawn in trains by tractors from a central plant or yard and distributed about the city to be individually pulled up and down the streets 10 and alleys to collect the ashes or garbage as the case may be. When the individual trailers are filled or have completed their route, they are assembled at a designated point into trains and the tractor hitches onto the train and pulls it back 15 to the receiving plant or dump. In pulling these trains along the city streets, other traffic is encountered. The trains must be moved to and from the collecting districts with speed, otherwise, a delay would require either more trailers 20 or a longer period of waiting by the collecting men for the return of the trailers. Moving the train of trailers at speeds from twenty to thirty miles per hour through traffic entails some risk unless the trailers remain exactly in line. Here- 25 tofore, couplings employed to connect the trailers have permitted a weaving of the trailers in the train and many accidents have occurred by this weaving action, in which a trailer would swing out of the straight line and side-swipe a vehicle 30 at the side thereof.

It is a primary object of my invention to provide a coupling by which a number of trailers may be hooked together to make up a train and those trailers remain in line as the train is moved 35 so as to eliminate the danger arising from the trailers weaving in and out laterally in a serpentine manner. A slight weaving in the old style couplers would soon multiply into a weaving of considerable magnitude. My invention pre- 40 vents the initiation of the weaving so that it is stopped or rather prevented before any multiplication of it sets in.

An important advantage of my invention is that the operators may couple trailers together 45 without danger of catching their fingers or hands between coupling heads. A further important feature of the invention is to be found in the fact that there is no lateral lost motion or play between the various parts entering into the coupling means, and while the lateral play is eliminated, the coupling is flexible vertically to provide for varying trailer end elevations.

These and other objects and advantages will 50 become apparent in the following description of

the invention as illustrated in the accompanying drawings, in which,

Fig. 1 is a fragmentary vertical, longitudinal section through a coupling structure embodying my invention as applied to the front and rear 60 ends of adjacent trailers of a train;

Fig. 2, a fragmentary top plan view of the coupling structure;

Fig. 3, a vertical transverse section on the line 3—3 in Fig. 1;

Fig. 4, a vertical transverse section on an enlarged scale on the line 4—4 in Fig. 1;

Fig. 5, a detail in fragmentary side elevation of tongue connecting means; and

Fig. 6, a fragmentary top plan view of the 70 tongue connection detail.

Like characters of reference indicate like parts throughout the several views in the drawings.

The chassis frame 10 of a rear trailer 8 is provided with a fixed cross member 11 near its 75 outer end, here shown as being a channel bar with its legs turned upwardly and located above the axle 12. A yoke 13 is bolted to the under side of the member 11, and the drawbar, generally designated by the numeral 14, is pivotally se- 80 cured between the cross member and the yoke. The drawbar 14 is built up by turning a structural channel 15 over a like channel 16 to have the outer edges of the respective channel legs abut each other, and these edges are welded one to 85 the other so that a hollow elongated box is produced. A casting 17 is fixed within the channel 15 and a like casting 18 in the channel 16, the two castings being vertically aligned and bored through to receive the king pin 19 with a forced 90 fit therein. The pin 19 is made of sufficient length to extend to above and below the fabri- cated drawbar and these projecting ends are re- duced in diameter to fit respectively revolubly in the bearing block 20 fixed on the cross member 95 11 and in the bore provided in the yoke 13. The drawbar 14 carrying the pin 19 in a fixed manner may then be rocked transversely under the cross member 11. The drawbar 14 extends forwardly from the king pin 19 to over the transverse bar 100 21 which is suspended from the chassis frame 10 a sufficient distance to allow the drawbar 14 to be shifted laterally over the bar 21 while in sliding contact with the underside of the chassis front cross member 22. By thus supporting the 105 outer end of the drawbar 14, vertical rocking action about the king pin 19 is prevented.

The drawbar 14 extends rearwardly from the king pin 19 a distance and carries a pin 23 ver- 110 tically disposed therethrough. This pin 23 has

an equalizer bar 24 carried on its lower end by a nut 25 which compressively forces the bar 24 up against a bearing washer 26 which in turn is forced against an annular shoulder about the pin. 5 This shoulder is at the lower end of a portion of the pin having a larger diameter, which portion revolubly fits within a bearing fixed to the under side of the drawbar. A nut 27 screwthreadedly engages the upper end of the pin 23 which extends 10 above a bearing block 28 fixed on the top side of the drawbar. The major part of the pin 23 which is within the bearing 28 has a larger diameter than that of the end thereabove. A washer is carried under the nut 27 so that by tightening 15 down the nut 27, the pin 23 is lifted to pull the lower washer 26 against the under bearing. Drag links 29 and 30, Fig. 2, are rockably fixed to the outer ends of the equalizer bar 24 and extend downwardly and outwardly to engage rockably 20 with the respective steering arms 31, 32, whereby the wheels 33, 34 may be steered upon shifting the drawbar 14 about the king pin 19 in the usual manner well known to those versed in the art.

A coupling head 35 is provided with a shank 36 25 formed to enter within the outer end of the drawbar 14 with a close sliding fit. A U-shaped yoke 37 has its ends brought up from the rear of the shank to straddle and be in contact with the vertical faces of the shank, and is there secured by 30 the pins 38 to extend back to within the drawbar. Two blocks 39, 40 are placed within the yoke 37, one against the rear end of the shank 36 and the other back against the end of the yoke. A compression spring 41 is placed within the yoke be- 35 tween the two blocks normally spacing the blocks apart and holding them in the positions above indicated. Each block is cut through vertically to form a central slot extending fore and aft and pins 42 and 43 are inserted vertically through the 40 drawbar 14 to pass respectively through these slots. The pins are so located in the drawbar that the pin 42 is at the extreme forward end of the slot in the block 39 while the pin 43 is at the extreme rear end of the slot in the block 40. 45 Thus, should the head 35 be forced back, the block 39 will remain stationary against the pin 42, but the shank 36 will press the block 40 back along the pin 43 to compress the spring 41, the rearward travel being limited by the length of the slot in the block 40, and conversely, should the head 35 be jerked ahead, the block 40 remains stationary while the yoke 37 carries the block 39 against the spring 41. The rear end of the yoke 37 is provided with a shim 63 on each vertical face so as 50 to provide a close sliding fit with the interior side walls of the drawbar and prevent lateral rocking of the head 35 relative to the drawbar. A yoke 46 is rockably carried by the head 35 to be free to swing vertically but prevented from swinging horizontally. On the outer end of the yoke is integrally carried a ring 45.

The foregoing structure is illustrated by the drawings as being located at the front end of a back trailer 8. The same identical structure is 55 employed at both ends of every trailer to be hooked up in a train, and I here show that same structure as applied to the rear end of the trailer 9 next ahead of the trailer 8, the parts on the trailer 9 identical with those on the trailer 8 being indicated by the corresponding numbers but primed.

Both coupling heads 35 and 35' are hollowed out from their outer vertical faces each to have a pocket 44' as shown in the head 35' within 75 which the ring 45 of the coupling yoke 46 may

enter and fit snugly against the back wall thereof. A coupling pin 47' is provided to slide vertically from the top down through this pocket and through the ring 45. The internal diameter of the ring 45 exceeds the diameter of the pin 47' 80 and the pin is spaced out from the rear pocket wall a distance less than the radius to the outside of the ring and just sufficient to let the ring slide between the pin and the wall. The pocket wall back of the pin and to either side thereof is semi-cylindrical in shape and its curvature conforms to that of the ring so that the ring may have no lateral play within the head although the pin 47' is of much less diameter than that of the hole through the ring. The walls leading from the 85 sides and top and bottom of the pocket flare outwardly to serve to guide the ring to within the pocket. The vertical height of the pocket exceeds that of the ring 45 so that the ring may be raised and lowered along the pin 47'. The radial cross-sectional shape of the ring 45 is that of a circle so that there is a point contact of the inner side of the ring with the pin, and a transverse line contact of the ring with the wall of the 90 pocket.

In coupling a rear trailer 8 to a forward trailer 9, the drawbar 14' of the forward trailer 9 is first secured in its central position by rocking the lock handle 48' to lower the dogs 49' and 50', one on each side of the drawbar 14', Fig. 4, whereby the 95 drawbar 14' may not be shifted laterally about its king pin and consequently the rear wheels of the trailer are thus held in the "straight ahead" position. The two trailers 8 and 9 are then brought one toward the other, the coupling pin 100 47' lifted, the yoke 46 held up by hand to guide the ring 45 to within the head 35' and the pin 47' then dropped down through the ring 45, thus 105 coupling the two trailers together. The drawbar lock handle 48 on the trailer 8 is shifted to release the drawbar 14 so that as the forward trailer 9 deviates from the straight line travel, the drawbar 14 may be rocked laterally about its king pin to steer the front wheels accordingly of the trailer 8. The particular details of the drawbar 110 locking means are shown in Figs. 2 and 4, but do not enter specifically into my invention since other means may be employed for the same purpose. The handle 48' has a crank 51' which fits within a vertical slot in a transversely shiftable 115 plate 52' which has inclined surfaces to be in the paths of pins 53' rearwardly extending from the dogs 49' and 50' so that as the handle 48' may be rocked in one direction the plate will be shifted to raise the dogs, and in the other direction to lower 120 them, springs 54' being employed to urge the dogs downwardly.

The yoke 46' on the forward head 35' is allowed to hang downwardly and is unused with the trailer being pulled forwardly. Should the trailers be moved in the reverse direction, the yoke 46 would be dropped and the yoke 46' raised and coupled in the head 35, and the drawbar 14' released and the drawbar 14 fixed in position as to lateral movement. The yoke 46 is in reality but a vertically hinged extension of the drawbar 14 and its ring 45 is always maintained to be centrally located of a central vertical plane through the drawbar 14. Side-whip of the drawbar 14 is prevented by reason of the close fit of the ring 45 in 140 the head 35' although, the ring 45 may slide circumferentially in the head when the trailers are pulled in curving lines.

By reason of the employment of the yoke 46, it will be observed that the drawbar 14 ahead 145

of its king pin on the drawn trailer is lengthened as to its lever arm by the length of the yoke 46, as compared to the shorter length of the corresponding lever arm of the drawbar 5 14' on the pulling trailer. By reason of this difference in lever arm lengths between the fixed forward, pulling drawbar and the laterally shiftable pulled drawbar, the amount of side-whip or weaving of the rear end of the pulling trailer 10 9 is greatly reduced, and for all practical purposes is totally reduced, as being transmitted to the front wheels of the pulled trailer 8, by reason of the greater lever arm length being provided on the steering drawbar of the pulled 15 trailer. Also, corners may be turned to better advantage by long trains of trailers employing my invention.

When the trailers are to be pulled individually by teams, the yoke 46 is rocked upwardly 20 and the rear end of a tongue 55 having a vertically slotted end is inserted to under the yoke and by that end to within the head 35 to straddle the coupling pin 47, Figs. 5 and 6. The yoke 46 is rocked down against the top side of the 25 tongue to have the downturned legs 65, 66 straddle the tongue and pass along the forward sides of the ears 57 and 58 fixed on the respective sides of the tongue whereby the tongue ears may bear against the yoke legs so that the trailer 30 may be pulled through the tongue. A back-turned lip 59 is provided on the yoke, over which lip a spring pressed pin 60 carried by the tongue may engage to prevent accidental lifting of the yoke off of the tongue.

35 While I have herein shown and described my invention in the one form in somewhat minute detail, it is obvious that structural changes may be made in that form without departing from the spirit of the invention, and I therefore do 40 not desire to be limited to that precise form any more than may be required by the following claims.

I claim:

1. In a trackless vehicle steerable coupling 45 having a drawbar, and having a king pin securing the drawbar to the vehicle to permit horizontal shifting thereof, and having a vehicle wheel steering means connected to said drawbar, and having a head on the drawbar, a yoke 50 horizontally straddling the head and rockably secured thereto to swing vertically, a ring on the outer end of the yoke, said head having a pocket therein with an inner wall conforming to the outer end of said ring, a coupling pin adapted to be inserted vertically in said head to extend through said pocket, and means for selectively retaining said drawbar in a straight-ahead position.

2. In a coupling between a pulling and a pulled 60 trackless vehicle having drawbars of identical construction on the opposing ends of the two vehicles, and having a vertically disposed king pin pivotally securing each drawbar to the respective vehicle to permit horizontal rocking of the drawbar, and having a vehicle wheel steering means connected with each of said drawbars, means on each of said vehicles to hold selectively said drawbars in straight ahead steering positions, said means being in the retaining position on the pulling vehicle and non-retaining 65 position on the pulled vehicle, a coupling yoke straddling and hinged to the drawbar of the pulled vehicle to swing vertically only, and a coupling pin carried by the drawbar of the pulling vehicle engaging the forward end of said

yoke, said yoke forming a laterally rigid but vertically yielding extension of the pulled drawbar to provide an increased length thereof as compared to that of the fixed pulling drawbar.

3. In a steering coupling between a pulled and a pulling trackless vehicle, a horizontally swingable drawbar on both vehicles, vehicle wheel steering means for each drawbar connected with a respective swingable drawbar, a yoke on the pulling vehicle straddling and hinged to the swingable drawbar to swing vertically, said swingable drawbar having a longer effective length than that of the yoke, a coupling pin detachably securing the drawbars together and a pivot pin for each drawbar located between the points of attachment of the steering means and the coupling pin.

4. In a steerable coupling between a pulled and a pulling trackless vehicle having a drawbar horizontally swingably mounted on the pulled vehicle, and having vehicle steering means connected with said drawbar, a drawbar mounted on the pulling vehicle and held in fixed position, a hinged coupling member carried by the swingable drawbar constrained to swing vertically only, an eye on the outer end of the coupling member, and a coupling pin carried by the pulling drawbar to pass through said eye, said coupling member causing the horizontally pivoting point between the two drawbars to be nearer 100 to the pulling vehicle than to the pulled vehicle.

5. In a trackless vehicle steerable coupling having a drawbar and having a king pin securing the drawbar to the vehicle to permit horizontal shifting thereof and having a vehicle wheel steering means connected to said drawbar, and a head on the drawbar, a yoke horizontally straddling the head and rockably secured thereto to swing vertically, a ring on the outer end of the yoke, said head having a pocket therein with an inner 115 wall conforming to the outer end of said ring, a coupling pin adapted to be inserted vertically in said head to extend through said pocket, and means for selectively retaining said drawbar in a straight-ahead position, said ring having an 120 internal diameter greatly exceeding the diameter of the coupling pin, and said coupling pin being located to hold said ring slidably but snugly against the sides of said pocket wall.

6. In a trackless trailer coupling having a 125 drawbar horizontally rockably attached to a trailer and having trailer wheel steering means connected to the drawbar and having a coupling head on the drawbar, a yoke having its legs rockably secured to the head to constrain the movement of the yoke to vertical travel in relation to the head, a coupling eye on the outer end of the yoke, said head having a pocket therein with side walls spaced apart a distance to provide for a sliding fit therebetween of a corresponding coupling eye, and a coupling pin adapted to be passed vertically through said head through said pocket.

7. In a trackless trailer coupling having a drawbar horizontally rockably attached to a trailer, trailer wheel steering means connected to the drawbar, a coupling head on the drawbar, a yoke having its legs rockably secured to the head to constrain the movement of the yoke to vertical travel in relation to the head, a coupling eye on the outer end of the yoke, said head having a pocket therein with side walls spaced apart a distance to provide for a sliding fit therebetween of a corresponding coupling eye, and a coupling pin adapted to be passed vertically through said head through said pocket, a trailer 140 145 150

tongue having a slotted end adapted to fit within said head pocket and straddle said coupling pin, ears extending from the tongue and legs depending from said yoke adapted to fit over the front 5 sides of said ears.

8. In a trackless trailer coupling having a drawbar horizontally rockably attached to a trailer, trailer wheel steering means connected to the drawbar, a coupling head on the drawbar, 10 a yoke having its legs rockably secured to the head to constrain the movement of the yoke to vertical travel in relation to the head, a coupling eye on the outer end of the yoke, said head having a pocket therein with side walls spaced apart 15 a distance to provide for a sliding fit therebetween of a corresponding coupling eye, and a coupling pin adapted to be passed vertically through said head through said pocket, a trailer tongue having a slotted end adapted to fit within 20 said head pocket and straddle said coupling pin, ears extending from the tongue and legs depending from said yoke adapted to fit over the front sides of said ears, said tongue being inserted under said yoke, and latch means on the tongue 25 adapted to engage said yoke to prevent accidental lifting of the yoke from the tongue.

9. In a trackless vehicle, a frame, a drawbar, a king pin securing the drawbar, said drawbar

being hollow forwardly of said king pin, a cross bar vertically supporting the forward end of the drawbar, a coupling head having a shank closely fitting slidably within the drawbar, a yoke fixed to said shank and extending back into said drawbar, a pair of shiftable blocks within the yoke, a compression spring normally spacing apart the blocks to yieldingly force them respectively against the rear end of the yoke and the rear end of said shank, said blocks being vertically slotted fore and aft, and pins carried by the drawbar extending vertically through said block slots to be normally respectively at the forward end of the slot of the rear block and at the rear end of the front block slot, shims at the sides 90 of said yoke to prevent lateral travel thereof within said drawbar, and a vertically swingable yoke hinged to said head.

10. In a coupling for a plurality of vehicles, a drawbar for each vehicle, a member pivoted to one of said drawbars to swing vertically said member having a coupling eye on its outer end, the other of said drawbars being recessed to receive the coupling eye without lateral play and a coupling pin passing vertically through the 100 recess and eye.
